UNITED STATES PATENT OFFICE

HUGO GERNSBACK, OF NEW YORK, N. Y.

CODE-LEARNER'S INSTRUMENT

Application filed August 16, 1929. Serial No. 386,376.

This invention appertains to new and useful improvements in educational appliances and more particularly to a novel device for facilitating the learning of dot and dash codes.

The principal object of the invention is to provide a learner's instrument of the character mentioned which because of its extremely simple construction can be manufactured at a very reasonable cost.

Another important object of the invention is to provide a code learner's instrument which will produce a clear snapping sound when actuated so that a person may clearly 15 detect the intelligence being transmitted, providing two parties are practicing with these instruments.

During the course of the following specification and claims, other important objects 20 and advantages of the invention will readily become apparent to the reader;

In the drawings:

Figure 1 represents a perspective view of the instrument in its entirety.

25 Figure 2 represents a longitudinal sectional view through the instrument.

Figure 3 represents a transverse sectional view through the sound producing element.

30 Figure 4 represents a transverse sectional view through a slightly modified form of the invention.

Referring to the drawings wherein like numerals designate like parts, it will be seen 35 that this novel instrument includes a rectangular shaped base 5 of any suitable material, preferably of a material reasonable in cost.

An elongated spring plate 6 has one end 40 provided with an opening for receiving the bolt 7, which bolt has a head 8, and interposed between the head and the edge portion of the said opening is a washer 9. The threaded end portion 10 of the bolt is engageable within a threaded opening in the base 5, and as clearly 45 shown in Figure 2, said bolt is disposed longitudinally through the bore of a cylindrical spacer 11.

The spacer by being interposed between the 50 plate 6 and the base 5 will maintain that por-

tion of the plate 6 projecting beyond the spacer 11 in substantial spaced parallelism with respect to the base 5.

The free end portion of the plate 6 is provided with an opening therein through which 55 the screw 12 is disposed for threaded engagement within the knob 13 which knob is thus secured upon this end portion of the plate 6 in the manner substantially as shown in Figure 2.

In order to produce a sound each time the 60 plate 6 is flexed, a depression 14 is provided in the plate at the approximate point the same will flex when pressure is applied on the knob 13. The size of the spacer 11, the 65 extent and width of the plate 6 and other factors may require the placement of this depression at some more favorable point on the plate, but of course, the disposition of the depression can be changed without departing from the spirit and scope of the invention 70 as claimed hereinafter.

It will be observed, that the base 5, the 75 spacer 11, and the knob 13 are each constructed of an insulating material, such as bakelite, fiber, glass or the like, but it is to be understood that these parts have been thus represented more as a matter to simulate real telegraph keys, than any particular advantage inherent therein. There parts can 80 be manufactured of any material, excepting that the plate 6 must have the necessary spring consistency to perform the function desired.

Figure 4 represents a modification of the 85 invention in that the base and spacer 5' and 11' respectively are constructed integrally. In other words, to reduce the cost of manufacture, these two details of the invention are constructed out of the same piece of material. It is also to be understood that the plate 6 may be suitably constructed at its 90 free end to provide a knob for use in lieu of the knob 13, shown in drawings. By constructing the plate 6 and knob of one piece 95 of material, and the base 5' and spacer 11' of another piece of material, the entire device may be manufactured at a cost under-pricing the structures shown in Figures 1, 2 and 3.

Having thus described the invention, what is claimed as new is:

1. A code learner's key comprising a base having a threaded opening in one end thereof, a spring arm, a spacing body having a bore therethrough, said body being adapted for disposition over one end of the base with its bore in registry with the opening in the base, and a bolt for securing the arm to the body and base, said bolt being disposed through the bore in the spacing body and threadedly engaged in the opening of the base.
- 10 2. A code learner's key comprising a base having a threaded opening in one end thereof, a spring arm, a spacing body having an opening therethrough, said arm being provided with an opening for registry with an opening of the spacing body, and a securing member for disposition through the registered openings of the said arm, spacer and base.
- 15 3. A code learner's key comprising a base, a spring arm, a spacing member for interposition between one end of the arm and one end of the base, and means for detachably connecting the arm and spacing member to the base.
- 20
- 25

In testimony whereof I affix my signature.

30 HUGO GERNSBACK.
